UNITED STATES PATENT OFFICE.

LEONARD ATWOOD, OF PHILADELPHIA, PENNSYLVANIA.

CONTINUOUS HYDRO-EXTRACTOR.

SPECIFICATION forming part of Letters Patent No. 700,112, dated May 13, 1902.

Application filed May 15, 1901. Serial No. 60,372. (No model.)

To all whom it may concern:

Be it known that I, LEONARD ATWOOD, a citizen of the United States, residing in Philadelphia, Pennsylvania, have invented certain

5 Improvements in Continuous Hydro-Extractors, of which the following is a specification.

My invention relates to certain improvements in hydro-extractors used in breweries, paper-mills, laundries, sugar-refineries, &c., 10 wherein moisture is to be extracted from material.

The object of my invention is to improve the construction of machines of the character described, so that the material can be fed to 15 the machine and discharged therefrom continuously, and at the same time to provide means whereby the said material can be thoroughly cleaned by causing water or other fluid to be projected against it.

20 In the accompanying drawings, Figure 1 is a vertical sectional view of my improved hydro-extractor. Fig. 2 is a sectional plan view on the line 2 2, Fig. 1. Fig. 3 is a sectional plan view on the line 3 3, Fig. 1, and Fig. 4 is a view showing the location of my improved apparatus in connection with a system of tanks or receivers.

25 A is the casing of the apparatus, supported on a suitable foundation-plate A', and in this 30 foundation-plate is a step-bearing c for a vertical driving-shaft C, provided with a bearing c' at its upper end. On the upper end of this shaft is a driving-pulley C', through which motion is given to the said shaft.

35 Secured to the shaft is a base-plate B, a portion of this plate being in the form of a wheel having a hub b, spokes b', and a rim b''. The spokes are in the form of blades and are set on an incline, as shown in Fig. 3, so that 40 any material coming in contact with said blades will be quickly removed from the casing and discharged through the outlet-openings a in the bottom plate A'.

The base-plate B carries an outer revolving casing B', on which is supported the internally-flanged ring B'', which has extending from its lower flange to the flange b'' of the base-plate B a conical screen E, supported at the center by a ring E', having perforations 45 e. Stay-rods e' are mounted back of the

screen E to support the same against pressure of the material being acted upon. In the casing B' are openings e'', which allow for the escape of the liquor extracted from the material.

55 Mounted loosely on the shaft C within the conical screen E is a frame D. This frame is suspended by ropes or chains g, which pass around pulleys g' and have attached to them counterbalance-weights G, by means of which the said frame can be raised and lowered at will within the casing. The frame D has a perforated conical shell d, and this shell is supported at intervals by horizontal partitions d', dividing the frame in the present instance into four compartments F F' F'' F'', and these several compartments are supplied with water or other fluid through pipes f f' f'' f'', respectively, connected by flexible sections of tubing to a supply-main D'. The perforations in the shell d are preferably so formed as to project the water downward against the screen E.

60 Extending from the bottom compartment of the frame D are two or more pipes f' with 70 their ends turned out, so as to force water against the bottom portion of the screen and cause the material as it is forced down the screen A to be dislodged and fall into the path of the rapidly-revolving blades b'.

65 In operation the material is fed into the space between the screen E and the frame D through a supply-pipe H and the waste liquid is carried off through the pipe I, as clearly 75 shown in Fig. 4, while the material from which the liquid is extracted is discharged through the openings a into a receiver M, situated below the hydro-extractor. If, for instance, the hydro-extractor is used in the manufacture 80 of paper, a plant such as shown in Fig. 4 may 85 be used, in which A is the extractor, M is a tank situated below the same, N is a second tank situated alongside of the tank M, and P is a beating-engine connected to said tank N through a pipe p.

90 Situated above the hydro-extractor is tank Q, from which the material may flow to the 95 extractor through the passage q, the said tank being connected to a centrifugal pump R by means of a pipe r, and this pump in turn is 100

connected to the tank N by a pipe r' and to the tank M by a pipe r^2 . The two pipes r' r^2 and the pipe r are each provided with a valve.

S is an overflow-pipe leading from the chest 5 or tank Q and communicating with valved branch pipes s s' , one leading to the tank M and the other to the tank N.

I is the waste-pipe leading from the hydro-extractor A, and D' is a water-supply pipe 10 communicating with the several feed-pipes in connection with the compartments in the frame D.

By this apparatus material can be fed in a 15 continuous stream through the extractor, and for this purpose I may employ any number of beating-engines P, discharging into the tank M, the contents of this tank being pumped by the centrifugal pump directly into the chest Q, which feeds the hydro-extractor.

20 The said extractor discharges the material directly into the tank M, and, if desired, the tank N may be cut off and the material in the tank M passed over and over again through the extractor by a proper adjustment of the 25 valves. Thus in treating such material as newspaper-stock, which contains a consider-

able amount of ink, the ink can be thoroughly extracted from the pulp, as the water or other fluid projected against the thin layer of pulp 30 on the screen E washes the pulp, causing the waste or dirty water to pass into the space between the screen E and the casing on the frame D and to the waste-pipe. The water can be projected from the casing against the 35 pulp on the screen in such quantities as to dislodge the pulp and cause it to pass down through the extractor in spite of and against the centrifugal force which would otherwise cause it to move upwardly on the screen E.

40 I claim as my invention—

1. A hydro-extractor having a perforated conical shell, a conical water-chamber within said shell and means for forcing water into the chamber and through perforations in the 45 walls thereof, with a device in the lower por-

tion of shell for facilitating the removal of material therefrom after its liquid has been extracted, substantially as described.

2. A hydro-extractor having a casing, a perforated shell within the same, a water-chamber within the shell having perforations in its walls and a device in the lower portion of the shell for facilitating the removal of material therefrom after its liquid has been extracted, substantially as described. 50

3. The combination in a conical perforated casing, means for revolving the same, said casing having an open bottom, a bladed wheel in the bottom, means for supplying material to the shell, a conical water-receptacle having a 60 perforated body, and means for feeding water to said shell, substantially as described.

4. The combination in a conical perforated casing, of means for revolving the same, said casing having an open bottom, a bladed wheel 65 in the bottom, means for supplying material to the shell, a conical water-receptacle having a perforated body, and means for feeding water to said shell, the body of said water-casing having inclined discharge-openings, substan- 70 tially as described.

5. The combination in a conical perforated casing, means for revolving the same, said casing having an open bottom, a bladed wheel in the bottom, means for supplying material to 75 said shell, a conical water-receptacle having a perforated body, and means for feeding water to said shell, the body of said water-casing having inclined discharge-openings, with a discharge-pipe at the bottom for loosening 80 the material so that it will pass away from the machine, substantially as described.

In testimony whereof I have signed my name to this specification in the presence of two subscribing witnesses.

LEONARD ATWOOD.
